UNITED STATES PATENT OFFICE.

JOHN J. MASON, OF BROOKLYN, NEW YORK.

TYPE-WRITER.

1,182,499.

Specification of Letters Patent. Patented May 9, 1916.

Application filed May 24, 1915. Serial No. 29,970.

To all whom it may concern:

Be it known that I, JOHN J. MASON, a citizen of the United States of America, residing at Brooklyn, in the county of Kings and State of New York, have invented certain new and useful Improvements in Type-Writers, of which the following is a specification.

My invention relates to typewriters and consists in the devices hereinafter described and claimed, whereby provision is made for writing in a peculiar way and upon particular substances.

In general it consists in mechanism which permits the machine to be used for filling in stiff cards such as are used for card indices. Then there are devices which enable me to write upon a semi-transparent substance and make a clear imprint, without destroying that substance.

Figure 1 is an upper face view of a typewriter of the Remington type, provided with devices embodying my invention, some parts being omitted and some parts shown in section to more clearly exhibit the mechanism of the parts I desire to show. Fig. 2 is a side view of the device of Fig. 1, but showing some details not shown in Fig. 1. Fig. 3 is, in the main, a central vertical sectional view of a part of the device of Fig. 1, showing also, in dotted lines, a type bar and its pivotal mounting. Fig. 4 is a sectional view of the roller or platen shown in Fig. 3, and the card and card carrier. Fig. 5 is a detail view of the line indicator and the pointer. Fig. 6 is a face view of one form of card, showing also words written thereon.

In filling out cards for an index it is desirable that provision be made for writing close to the extreme upper edge, in order that the matter may be readily seen while the card remains in the file, so that one sought may be found without spreading a series widely apart, and without removing others from the file. Again it is often desirable that the particular material closing what is known as the window space, which is that part occupied by the address in Fig. 6, may be properly located to receive a special matter, usually a name and address, so printed as to act as a stencil plate, without the necessity for that adjustment commonly required, since that occupies valuable

To attain the ends sought, I have

provided a carriage somewhat different from those in common use.

The front rod upon which the carriage runs is preferably dropped to the position indicated at 1, Fig. 2, and there supported on brackets 2, to give a clear space for the card frame and on this rod 1 and the rear rod 3, the rollers 4, 5 of the carriage are set. The rollers are mounted on axles journaled at the front in depending posts 6, extending downward from the frame of the carriage and at the rear in openings 7, formed in a part of said carriage. The carriage consists of the rear bar 8, carrying said rollers 5, a substantially rectangular frame 9, 10, 11, 12, hinged or pivoted to said rear bar 8, 70 as shown at 14, 15, cross pieces 16, 17, which extend forward and carry the posts 6, in suitable registry with rod 1, and from which posts 18 and brackets 19 rise, to support the frame 9, 10, 11, 12.

Between the cross pieces 16, 17, I secure the card frame, in the form of a plate 20, adapted to slide back and forth in grooves 21, formed in the bars 16, 17, and provided with racks 22, preferably on each side. The dropping of the front rod and the elevating of the front bar 12 of the rectangular frame give ample space for the insertion of the cards as well as for the movement of the card plate sufficiently to the front to permit said insertion. Said card plate or holder 20, is usually of a definite width to correspond with the card (or vice versa) and is provided with card stops 23, and leaf springs 24 for holding the card in place. It also has a suitable aperture or apertures 25, 26, so located as to uncover the parts of the card upon which the impressions are to be made.

Extending from part 10 to and through part 11 of the carriage there is a rod 27, journaled to rotate in bearings 28, secured to or forming part of the sides 10 and 11 of said frame. At one end this rod is secured to a coiled spring inclosed in drum 29 and set to turn said rod as do the hands of a clock, if viewed from the drum end. At the opposite end said rod carries a thumb piece 30 and just within the end there is an index drum 31, with figures, as shown, or other indicators arranged upon its periphery. This rod 27 also carries a roller or printing cylinder 32, provided with pinions 33, 33

registering and meshing respectively with racks 22, 22. At one side said roller 32 is also provided with a stop 34, which may be set in any one of the series of apertures 35, which are threaded to receive it.

Mounted on the frame, preferably on bar 12, there is a fixed stop 36, registering with the stop 34, and adapted to be engaged thereby when the cylinder is sufficiently rotated. A spring stop 37 is secured to the frame and registers with and engages the teeth of pinion or ratchet 38. It has a finger piece 38 for convenience in disengaging it. The line space pawl 39, carriage lever 40, lifting lever 41, and release lever 42 are substantially similar in form, arrangement and action to those of the ordinary machine, as is the trip bar 43 and spring tape 44, which is connected to an arm 45 extending from bar 8, though the trip bar is reversed to give more space and the spring 44 which restrains its movement is connected to bar 8.

The roller or cylinder is provided with two printing faces. For ordinary work, such as printing at the top line, there is the rubber face 46, but that would not answer when the so-called stencil is to be printed on the material occupying the window space 64. At that time a harder surface is required, which will not yield so much that the type will cut the material and yet will so sustain it that a sufficient impression may be made to permit the transmission of ink, so that it may be used as a stencil plate in marking the name and address it carries on other matter. For that purpose I have adopted a thin sheet of celluloid 47 and I secure it by means of a thin apertured steel plate 48, one end or edge secured to the roller 32, as at 49 and the other apertured as seen at 50, Fig. 1. Then by using a slotted turn button 51, whose slot engages the edge of the aperture at 50, I can loosen 45 the plate to remove the celluloid sheet or tighten it so as to hold it firmly in place by merely turning this button. The plate 48 has a window 52 which exposes the celluloid plate so as to permit its use as a printing 50 platen. Registering with the drum 31, there is a pointer 53. An arm 55, extends from the bar 8 and engages a collared sliding piece 56, mounted on stop rod 57 and limits the lateral movement of the carriage by engaging one of the marginal stops 59, 60, which are mounted on the stop rod 57 and held in predetermined positions by set screws 61, 62, and an extension 58 engages the other marginal slots. The card 63 has 55 a window space 64, closed by stencil material.

When a series of cards are to be written upon, the operator having chosen a blank which will fit the plate, brings the card 63 plate to the front by rotating the drum by

means of the thumb piece 30, and then inserting the card under spring 24 pushes it backward until it strikes against the stop 23, and then operates the rack and pinion until the card plate and card are at such 70 position that the type will strike the desired line on the card, usually that at the extreme upper edge as shown in Fig. 6. Then the operator sets the stop 34 in that aperture 75 35 which will bring it in engagement with stop 36. Once set the machine is ready to receive any number of such cards *seriatim*, without further adjustment and all that it is necessary to do to bring the card to the proper position for printing upon said line, 80 is to insert the card in the card frame and lift the stop 37 by means of finger-piece 38, when the spring in drum 29 will operate the pinions 33 and racks 22 to drive the frame, carrying the card, back to the proper 85 position, when stop 34 will engage stop 36, and arrest further movement. This is one prominent feature, since it saves all the time ordinarily required for adjusting a series of cards individually. Having once 90 made the adjustment noted, the operator, by means of thumb piece 30, moves the card frame forward until the first line of the window space 64 is at the printing point, and having done that loosens the set-screw 95 which holds drum 31, in place and turns it until the number 1, or other desired mark is opposite the pointer 53. Thereafter no further adjustment will be needed to insure that the address or other desired matter 100 will be printed on the desired lines, care having been taken to adjust the roller or printing platen so that the celluloid surface is at that time immediately over the window space 64. For subsequent cards of the 105 same series, it is only necessary to operate the thumb piece until the number 1 comes opposite pointer 53, without giving any attention to the card, since the operator knows that at that time the window and the printing platen will be in the desired position 110 with relation to the printing point. Printing on the other lines follows the usual order, they being brought to position by operating the spacing lever 40 or the thumb-piece 30, 115 as may be most convenient.

It will be manifest that a machine of this character will be of great use to mail order houses and other establishments that make use of a large number of cards for index purposes. Once set as described, the cards used being uniform, the filling in of a number of blanks is very rapidly accomplished, since no adjustment whatever is required for the first entry, and sometimes none for the others, as the lines succeed in regular spacing order, but if not, then such as is required is very rapidly done, without requiring experiment, by simply turning the thumb piece till the 120 125 130

proper number appears opposite pointer 53. Of course the number 2 or 3, or some other number may be selected as the line for beginning the address or whatever is to be written in the window space or any corresponding space, but the number 1 is usually selected as being more obviously the place to begin that entry.

Beside the saving of time and the insuring of accuracy, another feature of this device is that it permits the printing of the cards without bending them, thereby permitting the use of cards of sufficient body to more perfectly answer this purpose.

15. What I claim as my invention and desire to secure by Letters Patent is:—

1. In a type writer, a carriage provided with a card holder mounted to move back and forth upon said carriage and provided with a rack and a paper stop, a roller carrying a platen and provided with a pinion meshing with said rack, two stops adapted to engage each other, one connected with the carriage and the other with the card holder, one of said stops being adjustable to a series of positions, in each of which it will engage with the other of said stops and thereby arrest the retrograde movement of the card holder when a selected one of the series of lines across the card holder, suitably spaced from the paper stop, is at the printing line.

2. In a typewriter, the combination of a movable paper holder, a stop on said holder adapted to stop the paper at a given location, means for moving said holder, a spring for operating said means, a manually operated release for releasing said spring, a stop on the carriage adapted to limit the movement of the paper holder and a stop on the means whereby the paper holder is operated, adapted to engage the stop on the carriage, whereby the paper stop will hold the paper on given lines and the carriage stop will arrest the holder at limits adapted to leave a specified line across the paper-holder at the printing point.

3. In a typewriter, a carriage provided with a paper holder mounted to move back and forth upon said carriage and provided with a rack and a paper stop, a roller carrying a platen and provided with a pinion meshing with the rack, a stop connected with the carriage and a stop connected with the roller, adapted to engage one with the other when a given line across the holder has reached a given point, one of said stops being adjustable, whereby the line at which the carriage will stop may be varied.

60. 4. In a typewriter, a carriage provided with a card holder mounted to move back and forth upon said carriage and provided with a rack and a paper stop, a roller carrying a platen and provided with a pinion meshing with said rack, two stops, one on

the carriage and the other upon a part connected with the card holder, adapted to engage one another and thereby arrest the retrograde movement of the card holder when a given line across the card holder, suitably spaced from the paper stop thereon, is at the printing line, means for moving the holder, a spring whose tension is arranged to rotate said roller, an engaging device restraining the operation of the spring and a manually operated release adapted as described to release the spring restraining device, all substantially as set forth.

5. In a typewriter, a carriage provided with a card holder mounted to move back and forth upon said carriage and provided with a rack and a paper stop, a roller carrying a platen and provided with a pinion meshing with the rack, a stop on the carriage and a stop connected with the roller, adapted to engage one with the other when a given line of the holder has reached the printing point, together with a spring adapted to operate the pinion, a catch holding said spring and a manually operated release for releasing said spring from said catch.

6. In a typewriter, a carriage provided with a card holder mounted to move back and forth upon said carriage and provided with a rack and a paper stop, a roller carrying a platen and provided with a pinion meshing with the rack, a stop on the carriage and a stop connected with the roller, adapted to engage one with the other when a selected one of a series of lines across the holder has reached the printing point, together with a spring adapted to operate the pinion and a manually operated releasable detent, to hold said pinion.

7. In a typewriter, a plane reciprocating holder for the material upon which the printing is to be done, mounted in slots horizontally arranged on a carriage, provided with side bar frame portions, depending posts extending downward from the front parts of said side bar frame portions, rollers mounted in said posts, and a cross-bar connecting said posts, on a line below the level of said slots.

8. In a typewriter provided with a reciprocating paper holder mounted upon the carriage, a roller provided with a printing platen of one variety, and another harder printing surface independent of but extending over a portion of the periphery of the roller, but leaving a portion of the periphery of the first platen uncovered and exposed to the blow of the type, when at the printing line, a holder for the harder printing surface provided with an aperture, all arranged substantially as described, together with means for bringing each variety of printing surface to the printing line.

3. In a typewriter, the combination of a roller 32, carrying a printing surface 46, a part of which is uncovered, a second printing surface 47, harder than the first 3 and overlying a part of it and independent thereof, and a printing surface holder 52, with an aperture therein, all substantially as set forth.
10. In a typewriter, the combination of 10 a roller 32, carrying a printing surface 46, a part of which is uncovered, a second printing surface 47 harder than the first

and overlying a part of it, a printing surface holder 52, with an aperture therein and a locking device 51 for said holder 52, 15 all substantially as set forth.

In testimony whereof, I have signed my name to this specification in the presence of two subscribing witnesses, this 17th day of May, 1915.

JOHN J. MASON.
